Application December 29, 1939, Serial No. 311,692

2 Claims. (Cl. 5—23)

This invention relates to bed construction and more particularly to a folding sofa-bed comprising a piece of furniture having the appearance of a sofa by day and functioning as a double bed by night or when the occasion arises for the need of an extra bed. Prior to the instant invention it has been proposed that sofas be provided with folding springs and mattresses so that they may be unfolded to make up a double bed, but such constructions have been relatively expensive to manufacture and thereby incapable of universal use, particularly by those who are in most need of such dual purpose furniture but cannot afford the very high cost of prior constructions.

Not only have prior constructions been relatively expensive to manufacture, but they have been objectionable because of the fact that when the sofas are converted into beds, the temporary bed was too low for the occupant and left the impression with the occupant that he or she was sleeping on the floor or very close thereto. This disadvantage will be apparent when it is considered that sofa-beds are but temporary sleeping equipment and that the occupant has already been accustomed to sleeping in a bed of normal height.

It is an object of the instant invention to provide a piece of dual purpose furniture capable of being used for sitting in the day time and as a double bed at night, which piece of furniture will be relatively inexpensive to manufacture and comfortable when used for either sitting or sleeping.

It is a further object of the instant invention to provide a low cost mechanical sofa-bed of such construction as to make up into a comfortable sofa in the day time and into a double bed of normal height in the night time.

Other objects and the nature and advantages of the invention will be apparent from the following description taken in conjunction with the accompanying drawings, wherein:

Fig. 1 is a view in perspective of the sofa-bed in accordance with the invention in open position as a double bed;

Fig. 2 is a detail of the combined leg and hinge construction associated with the two sections of the double bed;

Fig. 3 is a detail of the rotatable support for the rear section of the double bed;

Fig. 4 is a transverse sectional view taken close to one end of the sofa, showing the bed sections in closed position in solid lines and the bed sections in partially open position in broken lines; and

Fig. 5 is a view similar to Fig. 4 with parts of the sofa broken away and with the bed sections in fully opened position.

Referring to the drawings, the sofa-bed 10 may comprise a conventional frame 11, back 12, side arms 13, and in addition the bed sections 14 and 15 which, when folded, make up the seat of the sofa as shown in Fig. 4.

The bed sections 14 and 15 are generally similar in construction, with the exception that the section 15 may be a little wider than the section 14 as best shown in Fig. 4, wherein the front portion of the section 15 is shown to overlap the frame 11, whereas the corresponding portion of the section 14, when the said section is in folded position, simply abuts the frame 11. These sections 14 and 15 which make up the sofa seat as well as the double bed, comprise an angle iron frame 16 to which may be attached wooden pieces 17 to facilitate the securing thereto of the outer fabric or other material that the upholsterer may use for this purpose. This angle iron frame supports a crisscross arrangement of wire 18 which in turn supports a plurality of coil springs 19. These coils 19 are tied together at their upper ends by a plurality of very small helical springs and the entire assembly is framed at the upper portions of the outer coil springs 19 by a wire margin whereby a complete spring unit is formed. The fabric 20 and stuffing 21 complete the bed section assemblies and give a comfortable appearance thereto.

In Fig. 3 the sofa is shown with the bed sections in closed position and the parts arranged for sitting purposes. Removable pillows, not shown, may be associated with the top of the bed section 15, if desired, or they may be dispensed with as the bed section 15 by itself is quite comfortable. The two sections 14 and 15 are supported within the sofa-bed 10, when the sections are in closed position, by the bolt 22 and the right angle element 23, one end of which is secured to the bed section 14 and the other end of which is pivotally secured to the frame of the sofa 10. Secured to the angle iron frame of section 14 is a pair of metal extensions 24 which may cooperate with corresponding extensions from the frame of the sofa when the sections are in closed position so that the said sections may be supported at the rear thereof. It is to be understood that it is within the spirit of the invention to utilize other stop means for supporting the sections when in closed position, which stop means may be simply a frame member positioned beneath the section 14 or otherwise in

association with the angle iron frame 16 of the sections 14 and 15.

When it is desired to open the sofa-bed from the position shown in Fig. 4 to that shown in Fig. 5, the rear of the bed section 15 is grasped and lifted upwards, while at the same time the front of the bed section is grasped by the other hand of the operator and moved outwardly to the position shown in broken lines in Fig. 4. This operation will effect pivotal action about the bolt 22 as also is shown in the broken lines in Fig. 4. Continued rotation of the element 23 about the bolt 22 and a straight horizontal pulling action on the front of the bed section 15 will bring the bed sections to the positions shown in Fig. 5. The combined legs and double pintled hinges 25 will automatically take the positions shown in Figs. 1 and 5 and the front legs 26 may be straightened to the positions shown in Figs. 1 and 5. The bed section 15 may be provided with strips at its front and rear, if desired, to facilitate the opening and closing of the sofa-bed 10. In order to make the construction sturdy and yet as inexpensive as possible, the legs 25 are of the proper length to support the sections 14 and 15 at comfortable bed height, as indicated in Figs. 4 and 5, and the upper portions thereof are associated with the adjacent corners of the angle iron frame 16 of the sections 14 and 15 by a pair of pintles 27 and 28, see Figs. 2 and 5, which may simply comprise loose fitting rivets or other suitable pintle elements. The legs 26 are pivotally secured at their upper portions 29 to the front part of the angle iron frame 16 of the section 15, whereby when it is desired to convert the bed sections into a seat for the sofa, the legs 26 may be rotated in a direction toward each other to a position within the angle iron making up the front part of the frame 16 for the section 15. It will be noted that the legs 25 automatically take care of themselves and when the bed sections 14 and 15 are closed, the legs 25 fit therein. This feature is perhaps best illustrated by the broken lines in Fig. 4.

In order to ensure that the bed sections will be in the proper sitting position when the sofa-bed 10 is closed and in the proper sleeping position at bed height when the sections 14 and 15 are opened, and in order that the mechanism ensuring such operation may be fabricated inexpensively without sacrifice of smoothness of operation, the bolt 22 is provided with a washer 30 which engages one side of the vertical leg 23v of the right angle element 23. Between the other side of the vertical leg 23v and the frame 11 is a helical spring 31 which serves as a bushing and spacer element 31 for the rotating right angle element 23. The bolt 22 extends through the frame 11 and is provided at its other end with a washer 32 and a nut 33. The horizontal leg 23h is secured to the frame 16 of the section 15 as already described.

It will now be understood that the construction set forth above permits of fabrication at low cost and that the resultant sofa-bed will be comfortable for both sitting and sleeping purposes. It will be noted that the simplest materials have been utilized and that no separate mattress is necessary for association with the bed sections 14 and 15 which are already upholstered for both sitting and sleeping purposes. The particular frame construction for the bed sections and the novel and inexpensive legs associated therewith are factors in keeping the cost of the construction at a minimum. The novel construction which permits the bed sections to be stowed away in the sofa-bed when the same is to be used for sitting purposes and effects the arrangement of the bed sections at a bed height level when the sofa-bed is to be used for sleeping purposes is particularly advantageous and makes for the great comfort of the user.

It will be obvious to those skilled in the art that various changes may be made in this device without departing from the spirit of the invention and therefore the invention is not limited to what is shown in the drawings and described in the specification but only as indicated in the appended claims.

What is claimed is:

1. In a sofa-bed having a common section utilized as a bed portion when the sofa bed is used as a bed and utilized as a seat when the sofa-bed is used as a sofa and the construction being such that the said common section is at relatively higher bed height level when the sofa-bed is used as a bed and at relatively lower seat level when the sofa-bed is used as a sofa comprising: a frame, a first bed section and a second upholstered innerspring combined seat and bed section, said sections being secured together in foldable relation and in such manner that the said second section is on top when the sections are folded by moving the second section toward the first section in a first rotary direction, an extension element pivotally secured to said frame and fixed to said first section, so that said first section may be swung relative to said frame in the opposite rotary direction, the pivot point being located on the frame at such distance from the bottom thereof, and the length of the extension element and the height of the upholstered second section each being such that when the foldable sections are in open bed position, the top of the second section is at bed height, which is higher than the level of the second section when the two sections are folded together in the frame.

2. The structure recited in claim 1, the pivotal relation between said first section and said frame being such that when said first section is swung into said frame, its outer edge will swing through an arc extending above bed or seat level of said sofa bed.

SAMUEL NUSINOW.
